UNITED STATES PATENT OFFICE.

MARCUS EINHORN, OF BROOKLYN, NEW YORK, ASSIGNOR TO LIGHTING APPLIANCE CO., INC., A CORPORATION OF NEW YORK.

DESIGN FOR A CHANDELIER OR ARTICLE OF ANALOGOUS NATURE.

Application filed December 12, 1928. Serial No. 29,239. Term of patent 3½ years.

To all whom it may concern:

Be it known that I, MARCUS EINHORN, a citizen of the Republic of Hungary and a resident of Brooklyn, county of Kings and State of New York, have invented a new, original, and ornamental Design for a Chandelier or Article of Analogous Nature, of which the following is a specification, reference being had to the accompanying drawing forming a part thereof:

The drawing shows a perspective view of the chandelier or article of analogous nature, which has arms for the support of candles or drop lights.

I claim:

The ornamental design for a chandelier or article of analogous nature substantially as shown and described.

MARCUS EINHORN.
